LATCH TRIPPING MECHANISM COMPRISING
ABUTTING PIVOTED MEMBERS

John F. Chipman, South Weymouth, Mass., assignor to Allis-Chalmers Manufacturing Company, Milwaukee, Wis.

Application May 8, 1950, Serial No. 160,652

7 Claims. (Cl. 74—2)

1

This invention relates generally to operating mechanisms for electric circuit breakers which are latched closed against an opening biasing force, and more particularly to tripping means for unlatching and causing opening of the circuit breakers by the biasing force.

Circuit breakers of this general type, and particularly multipole circuit breakers which are designed to interrupt heavy currents, are of rugged construction and usually employ strong springs to operate the contacts between closed and opened positions. The tripping device which cooperates with a releasable contact operating structure for normally latching a releasable member must be designed to withstand considerable strain because it absorbs part of the force of the contact operating springs when it unlatches the releasable member.

Tripping devices heretofore provided have been designed as a unitary structure, and the reactions of the contact operating mechanism during an unlatching operation have resulted in the creation of a given excessive amount of kinetic energy which must be absorbed before the tripping device comes to rest. If the weight of the tripping device were substantially decreased to reduce the kinetic energy resulting from the movement thereof, the device would not be able to stand the force transmitted to it from the contact springs.

In accordance with the invention claimed a new and improved tripping device is provided comprising a pivoted force receiving member and a pivoted force transmitting member. The force transmitting member upon movement thereof actuates the force receiving member to move a latch to release a member which operates a contact actuating structure. Upon release of the contact actuating structure, the force receiving member is further actuated in latch releasing direction by the contact actuating springs independently of the force transmitting member. The force transmitted to the tripping device by the contact actuating springs results in accelerating only a part of the tripping device and consequently the resultant kinetic energy produced is less than the kinetic energy produced by the unitary tripping devices heretofore used.

It is, therefore, one object of the present invention to provide a new and improved tripping device for unlatching electric circuit breakers in which a pivoted force receiving member is divorced during actuation of the tripping device from a pivoted force transmitting member.

Another object of this invention is to provide

2

a new and improved tripping device for electric circuit breakers in which a pivoted force receiving member and a pivoted force transmitting member cooperate to move together during an unlatching operation, but move independently of each other after the unlatching operation.

A further object of this invention is to provide a new and improved tripping device for electric circuit breakers in which a pivoted force transmitting member actuates a pivoted force receiving member upon actuation of the tripping device and arcing contact springs further actuate the force receiving member upon movement of the arcing contacts thereof.

10 Objects and advantages other than those set forth will be apparent from the following description when read in connection with the accompanying drawings in which:

Fig. 1 is a sectional view of an operating mechanism embodying the present invention;

20 Fig. 2 is an enlarged sectional view of a part of the tripping device illustrated in Fig. 1 taken along line II—II in Fig 3;

Fig. 3 is a front view of the embodiment illustrated in Fig. 2 with part of the elements removed; and

25 Figs. 4 to 6 show in cross-section three different positions of the tripping device and associated linkage by which the circuit breaker is operated and restrained in closed circuit position.

30 Referring more particularly to the drawing by characters of reference, Figs. 1 to 6 illustrate part of a magnetic blowout type circuit breaker 11 and an operating mechanism 12. The latter comprises a force transmitting structure 13 and a tripping means 14. Although circuit breakers of the type herein considered are frequently provided with a plurality of similar pole structures, one for each phase of a polyphase electric circuit, only one such pole structure or pole unit is shown in Figs. 1 to 6 and the circuit breaker will be described in detail as if it were of the single pole type.

35 Circuit breaker 11 illustrated in Fig. 1 includes as elements thereof a pair of terminal studs 15 (only one of which is shown) for connecting the circuit breaker to line conductors (not shown). Breaker 11 comprises essentially means for opening the circuit to form an arc, and an arc extinguishing structure. Specifically, the circuit opening means comprises a fixed arcing contact 16 and a movable arcing contact 17. Arcing contact 17 is mounted on a lever 18 which is pivotally mounted at 19 on an extension arm 20

55 of one of the circuit breaker studs (not shown).

and is operated by means of a connecting rod 21 of insulating material forming a part of the force transmitting structure 13 for operating the movable contact between closed and open circuit positions. Fig. 1 illustrates the movable arcing contact 17 in the closed circuit position.

For the purpose of interrupting the arc formed upon separation of the arcing contacts, an arc extinguishing structure, such as an arc chute 24 (partly shown in Fig. 1) is mounted directly above the arcing contacts so as to receive the power arc when it is driven upward by a magnetic blowout means 25. The arc chute is disposed directly above the arcing contacts, as shown, when the blowout means act upward, but may be mounted in any other suitable location when the blowout means act in other directions. The arcing contacts and the magnetic blowout structure can assume any suitable known form so that a brief description thereof will be sufficient. The magnetic blowout means 25 comprises a core 26, poles 27, and a coil 28 which is inserted in the connection between the terminal stud 15, contact 16 and an arc runner 29, so that the arc current (as the arc travels along the runner) flows through the blowout coil in a manner well known in the art. Core 26 and poles 27 embrace at least part of arc chute 24 for driving the arc into the chute and toward the exhaust end thereof.

The operating mechanism 12 illustrated is interposed between a solenoid 30 and the movable arcing contact 17. In the position shown in Fig. 1, the circuit breaker is in the closed position and the operating mechanism is held in such position by a pivoted locking latch 31 forming a part of tripping means 14 and a tripping linkage or toggle 32.

In addition to toggle 32 comprising links 35 and 36, the mechanism comprises a spring 37 which resiliently biases one end of link 35 to a frame 38. A bell crank 39 pivotally mounted to frame 38 at a point 40 has one arm thereof pivotally connected to link 36 and the other arm thereof pivotally connected at a point 41 to a connecting rod 42. A bell crank 43 is connected to rod 42 and to a connecting rod 21.

A contacting actuating spring means 45 is compressed between frame 38 and a collar 47 secured to one end of a connecting rod 46. The other end of rod 46 is pivotally connected to bell crank 39 at a point 41, whereby a force transmitting structure 13 is completed between spring means 45 and contact lever 18.

Tripping means 14 comprises a force receiving member and a force transmitting member to move latch 31 to release toggle 32. The force transmitting member comprises a trip bar 48 of U-shaped cross section more clearly shown in Fig. 2. Trip bar 48 is provided with a bore 49 engaged by a screw 50 which is surrounded by a helical biasing spring 51. Trip bar 48 forms an integral part of a structure comprising two lateral plates 54 and 55 (more clearly illustrated in Fig. 3) which are pivotally supported by a shaft 56. Plates 54, 55 may have a running fit on shaft 56, which may be if so desired supported for rotation in bearings (not shown) mounted on frame 38. The two plates 54 and 55 are each provided with a hole 57 which minimizes their weight. Plates 54 and 55 are rigidly interconnected by a tie bar 58.

The force receiving member of tripping means 14 comprises a block 59 in the shape of an irregular hexagon pivotally supported on shaft 56. The force transmitting and receiving members

thus are supported for pivotal movement about a common axis. The lower surface of hexagonal block 59 abuts against tie bar 58, which interlocks the force transmitting and receiving members. Block 59 is provided with a pin 60 against which a rat-trap spring 61 rests. Rat-trap spring 61 biases hexagonal block 59 in the counterclockwise direction into engagement with tie bar 58, thereby interlocking the force transmitting and receiving members during movement thereof in latch releasing direction. Block 59 is provided with a pair of extension plates 62 which are rigidly secured to and form an integral part of block 59 and serve as a bracket for a supporting pin 63. Pin 63 supports a link 64 which cooperates with plates 62 to form a toggle for controlling latch 31. A latch roll 67 is mounted on one arm of a bell crank 68, which is secured to shaft 56 if the shaft is rotatable. The other arm of bell crank 68 is connected to link 35 through a pin 69. Latch roll 67 of the tripping means 14 is normally held in position by latch 31. The position of bell crank 68 in turn determines the position of toggle 32. The force component transmitted from latch roll 67 to the latching surface of latch 31 is substantially normal to the latching surface and passes through the center of pin 66 around which latch 31 pivots. Latch 31 is held in position by link 64.

A toggle roll 70 is mounted on a pin which interconnects links 35 and 33 of toggle 32. Toggle roll 70 is arranged to move along surface 71 of frame 38 during the unlatching operation, thereby positioning toggle 32 so that it may jackknife under the force of spring 45.

Solenoid 72 comprising coil 74 and armature 75 is provided for reclosing circuit breaker 11. Upon actuation of solenoid 72, armature 75 applies a force to toggle roll 70 and moves toggle 32 to its over center position. For manual closing, the closing force is applied on link 35 by means of bell crank 76, the rotation of which is controlled through a link 77 attached to end of manual closing crank 78 located at the front of the breaker. A latch check switch 80 (illustrated in Fig. 2) needed for completion of the reclosing solenoid circuit is actuated by cam face 81 of the hexagonal block 59.

The actual tripping operation is best illustrated in Figs. 4 to 6 wherein Fig. 4 illustrates the circuit closed position of the operating mechanism 12, Fig. 5 an intermediate position of operating mechanism 12, and Fig. 6 the open position of operating mechanism 12. The mechanism being in the closed position of Fig. 4, the solenoid 30 is energized so as to actuate the force transmitting member of tripping device 14 a predetermined distance. The plunger of solenoid 30 abuts against the U-shaped trip bar 48, thus causing rotation of the lateral plates 54 and 55 in the clockwise direction about shaft 56. Block 59 resting on tie bar 58, which interconnects lateral plates 54 and 55, is also rotated clockwise upon clockwise movement of lateral plates 54 and 55 to break the toggle 62, 64. The breaking of toggle 62, 64 and the subsequent counterclockwise rotation of latch 31 releases the latch roll 67 of the restraining bell crank 68. Latch roll 67 rides out of the notch in latch 31 and is forced upward with toggle 32 by the reacting force of spring 45 acting on bell crank 39. Toggle 32 moves upward into the position shown in Fig. 5, thereby completely releasing spring 45 which instantaneously separates the arcing contacts.

Upon release of latch roll 67 from the notch 75 of latch 31 the force component transmitted from

latch roll 61 to latch 31 accelerates the unit comprising block 59, extension plates 62, pin 63, link 64 and latch 31, thereby unlocking the force transmitting and receiving means. This force component being directly proportional to the size of spring 45 and the degree to which it is compressed is of considerable magnitude and results, therefore, in a very high acceleration of the force receiving member of tripping device 14.

In accordance with the invention the force receiving member of tripping means 14 is divorced from the force transmitting member, and the reaction which is transmitted from the latch to the other parts of the force receiving member is not transmitted from the latter to the force transmitting member. The force receiving member is free to rotate in the clockwise or latch opening direction under the action of the latch reaction without affecting the force transmitting member, and the members reach the position thereof shown in Fig. 5. Because the force transmitting member is divorced from the force receiving member, the mass of the force receiving member may be much smaller than heretofore used, resulting in a substantial decrease of the kinetic energy that will be imparted to it, a reduction in the stresses imposed on the tripping device 14, and an increase in the over-all speed of operation of tripping devices 14.

While toggle 32 moves upward, roll 70 thereof rolls along surface 71 of frame 38 until toggle 32 reaches the over center position and collapses into the position shown in Fig. 6 through the biasing action of spring 37. Upon deenergization of solenoid 30, the force transmitting and receiving members of tripping device 14 return to their original position as shown in Fig. 6 through action of rat-trap spring 61.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. An operating mechanism comprising a force transmitting structure and tripping means controlling said structure, said tripping means comprising a collapsible toggle having one link thereof connected to said structure, spring means for causing collapse of said toggle and actuation of said structure, means including a latch for preventing collapse of said toggle, and means for actuating said latch to release said toggle comprising a pivoted force receiving member and a pivoted force transmitting member, said force transmitting member upon movement thereof actuating said force receiving member to move said latch to release said toggle, said toggle upon release thereof further actuating said force receiving member in latch opening direction independently of the movement of said force transmitting member.

2. An operating mechanism comprising a force transmitting structure and tripping means controlling said structure, said tripping means comprising a collapsible toggle having one link thereof connected to said structure, spring means for causing collapse of said toggle and actuation of said structure, means including a latch for preventing collapse of said toggle, and means for actuating said latch to release said toggle

comprising a force receiving member and a force transmitting member, said force receiving member and said force transmitting member arranged to interlock for pivotal movement together about a common axis in latch releasing direction, said toggle upon release thereof unlocking said members and further actuating said force receiving member in latch opening direction independently of said force transmitting member.

3. An operating mechanism comprising a force transmitting structure and tripping means controlling said structure, said tripping means comprising a collapsible toggle having one link thereof connected to said structure, a first spring means for causing collapse of said toggle and actuation of said structure, means including a latch for preventing collapse of said toggle, and means for actuating said latch to release said toggle comprising a pivoted force receiving member, a pivoted force transmitting member, and a second spring means for biasing said force transmitting member to interlock with said force receiving member during movement together in latch releasing direction, said toggle upon release thereof unlocking said members and further actuating said force receiving member in latch opening direction independently of said force transmitting member.

4. An operating mechanism comprising a force transmitting structure and tripping means controlling said structure, said tripping means comprising a collapsible toggle having one link thereof connected to said structure, spring means for causing collapse of said toggle and actuation of said structure, means including a latch for preventing collapse of said toggle, and means for actuating said latch to release said toggle comprising a pivoted force receiving member, a pivoted force transmitting member, and an abutting connection between said members for controlling the movement of said force transmitting member in one direction, said force transmitting member upon movement thereof actuating said force receiving member to move said latch to release said toggle, said toggle upon release thereof further moving said force receiving member in latch opening direction independently of the movement of said force transmitting member.

5. An operating mechanism comprising a force transmitting structure and tripping means controlling said structure, said tripping means comprising a first collapsible toggle having one link thereof connected to said structure, spring means for causing collapse of said toggle and actuation of said structure, means including a latch for preventing collapse of said toggle, and means for actuating said latch to release said toggle comprising a pivoted force receiving member, a pivoted force transmitting member, an abutting connection between said members for controlling the movement of said force receiving member in one direction, and a second collapsible toggle having one link thereof attached to said force receiving member and the other link thereof attached to said latch for locking said latch to restrain movement of said first toggle, said force transmitting member upon movement thereof actuating said force receiving member to collapse said second toggle and move said latch to release said first toggle, said first toggle upon release thereof further moving said latch and said force receiving member in latch opening direction independently of the movement of said force transmitting member.

70

6. An operating mechanism comprising a force transmitting structure and tripping means controlling said structure, said tripping means comprising a collapsible toggle having one link thereof connected to said structure, a first spring means for causing collapse of said toggle and actuation of said structure, means including a latch for preventing collapse of said toggle, and means for actuating said latch to release said toggle comprising a pivoted force receiving member, a pivoted force transmitting member, an abutment member secured to said force transmitting member for controlling the movement of said force receiving member in one direction, and a second spring means biasing said force receiving member into engagement with said abutment member, said force transmitting member upon movement thereof actuating said force receiving member against the bias of said second spring means to move said latch to release said toggle, said first spring means upon release of said toggle further actuating said force receiving member in latch opening direction against the bias of said second spring means independently of the movement of said force transmitting member.

7. An operating mechanism comprising a force transmitting lever, a bell crank having one arm thereof secured to said lever, a collapsible toggle having one link thereof connected to the other arm of said bell crank, a first spring means for causing collapse of said toggle and actuation of

5
10
15
20

said lever, means including a latch to lock said toggle in an over-center position, means for actuating said latch to release said toggle comprising a force receiving member, a force transmitting member, said members being supported for pivotal movement about a common axis, an abutment member secured to said force transmitting member for controlling the movement of said force transmitting member a predetermined distance in latch releasing direction, and a second spring means biasing said force receiving member into engagement with said abutment member, said force transmitting member upon movement thereof actuating said force receiving member against the bias of said second spring means to move said latch to release said toggle, said first spring means upon release of said toggle further actuating said force receiving member in latch opening direction against the bias of said second spring means independently of the movement of said force transmitting member.
